GAME BOARD

Arthur Louis Hirst, Halton, near Lancaster, and Vernon Mansell Bullock, Nether Kellet, near Carnforth, England

Application November 30, 1948, Serial No. 149,889
In Great Britain October 15, 1948

Term of patent 14 years

(Cl. D34—5)

To all whom it may concern:

Be it known that we, Arthur Louis Hirst, of Caerleon, Halton Green, Halton, near Lancaster and Vernon Mansell Bullock of Sunnycroft, Nether Kellet, near Carnforth, both in the county of Lancaster and Kingdom of England, both British Subjects, have invented a new, original, and ornamental Design for a Game Board, of which the following is a specification, reference being had to the accompanying drawings, forming part thereof.

Fig. 1 is a plan view of a game board showing my new design;

Fig. 2 is a left-hand side and center portion of the board drawn to an enlarged scale; and

Fig. 3 is a right-hand side and center portion of the board drawn to an enlarged scale.

The board is of conventional thickness.

I claim:

The ornamental design for a game board, as shown and described.

ARTHUR LOUIS HIRST.
VERNON MANSELL BULLOCK.
